UNITED STATES PATENT OFFICE.

SAMSON LOWENSTEIN, OF NEW YORK, N. Y.

HOISTING-BLOCK.

1,104,521.

Specification of Letters Patent. Patented July 21, 1914.

Application filed April 14, 1914. Serial No. 831,747.

To all whom it may concern:

Be it known that I, SAMSON LOWENSTEIN, a subject of the Czar of Russia, and a resident of the city of New York, borough of Manhattan, in the county and State of New York, have invented a new and Improved Hoisting-Block, of which the following is a full, clear, and exact description.

This invention relates to hoisting blocks, and more particularly to automatic clutches whereby the load sustained by the block or tackle may be locked or held in any desired position, and whereby dropping of the load is prevented while the operator is performing the act of hoisting the load.

The invention has for its general objects to improve and simplify the construction and operation of hoisting blocks and clutching mechanism therefor so as to be reliable and efficient in use, comparatively inexpensive to manufacture and readily manipulated.

Another object of the invention is the provision of a novel form of clutching dog which can be manually thrown out of clutching position with respect to the rope that passes through the block and which is equipped with a prop or other supporting means for holding the dog in thrown-out position, so as to enable the load sustained by the block to be lowered, such prop being so related to the pulley that it will be automatically released to allow the dog to drop to clutching position as soon as the hoisting of the load begins.

With such objects in view, and others which will appear as the description proceeds, the invention comprises various novel features of construction and arrangement of parts which will be set forth with particularity in the following description and claims appended hereto.

In the accompanying drawing, which illustrates one embodiment of the invention, and wherein similar characters of reference indicate corresponding parts in all the views, Figure 1 is a perspective view of the improved block shown applied to a painter's scaffold; Fig. 2 is an enlarged sectional view of the block taken parallel with the plane of the pulley; Fig. 3 is a central vertical section of the block; Fig. 4 is an edge view of the block; Fig. 5 is a horizontal section on the line 5—5, Fig. 2; Fig. 6 is a perspective view of a hoisting tackle showing the invention applied to the upper multiple

pulley block; and Figs. 7 and 8 are sections on lines 7—7 and 8—8, Fig. 6.

Referring to the drawing, A designates the block which is shown as of the single sheave type; B is the hoisting rope; C the scaffold supporting yoke suspended from the block and supporting the scaffold D. Obviously the block A may be used for hoisting and suspending any other kind of load.

The block A comprises a housing or body that includes a U-shaped frame or yoke 1 and side plates 2 suitably fastened to the said yoke. The lower end of the yoke constitutes a loop or eye to which is fastened a suspending hook or equivalent device 2a. The upper extremities of the side members 3 of the yoke are connected together by a bolt or equivalent means 4 which has an eye 5 around which the extremity 6 of the hoisting rope B is fastened. In the lower end of the housing or body of the block is a sheave or pulley 7 which rotates on an axle 8 formed by a bolt or equivalent means passing through the yoke 1 and side plates 2. The first run or flight b of the hoisting rope extends from the top of the block upwardly to an overhead pulley; the second run or flight b' extends downwardly into the block and passes under the pulley 7; the third flight or run b² extends upwardly to another overhead pulley, and the fourth or free run or flight b³ extends down to any suitable point where it can be operated.

The clutching means comprises a dog E which is fastened at its center to a crank shaft or axle 8', which axle extends out of the body or housing of the block and is provided with a throw-out crank 9. Both extremities are formed into eccentric serrated gripping faces 10 which are adapted respectively to engage the flights b' and b² of the hoisting rope and clutch the same against abutments 11 and 12 for the flights b' and b², respectively. Normally the double-ended dog is in the dotted line position, Fig. 2, during the act of hoisting, so as to be ready to grip the hoisting rope if the hoisting power should be accidentally released, and in this event the dog will clutch the rope against the abutments 11 and 12. The travel of the rope, however, during the act of hoisting maintains the dog released. The dog is adapted to be supported in inoperative position by means of a prop 13 which is pivoted at 14 to one end of the dog, so that the weight of the prop will operate to maintain

the dog in the dotted-line position during the hoisting operation. This dog has a free end 15 which is adapted to engage the periphery of the pulley 7 when the dog has been thrown to inoperative position, as shown by full lines in Fig. 2. The movement of the prop during the throw-out action is limited by a stop 16 fastened to the housing in such a position that the prop will have come to rest to one side of a line passing through the center of the pulley 7 and axis of the dog E. The prop is adapted to be thrown out of supporting position automatically by means of teeth 17 on the periphery of the pulley 7. When the dog is propped in inoperative position, as shown in Fig. 2, the load sustained by the block can be lowered without the dog interfering, but if it is desired to lift the load a pull will be exerted on the hoisting rope to move the same in the direction indicated by the full-line arrows, and consequently the pulley 7 will move in a clockwise direction, Fig. 2, and thereby trip the prop 13 and allow the dog to gravitate to dotted-line position, where it will be ready to grip the rope if the hoisting pull should be accidentally released. A yielding cam 18 is provided on the prop so as to engage a fixed stop or abutment 19 arranged in the body of the block just below the dog axle 8. This cam will prevent the prop 13 from occupying any except either extreme position. On the dog E is a buffer spring or equivalent means arranged to strike an abutment 21 to limit the throw-out movement of the dog when the crank 9 is operated. It will be understood that when the prop is in the full-line position shown in Fig. 2, the pulley 7 can freely pass in an anti-clockwise direction without the prop interfering, as the latter will ride up and down as the teeth of the pulley pass under the prop.

In the case of blocks of the multiple pulley type, as the block D', Figs. 6, 7 and 8, the double clutch dog E' has its end-gripping portions 10^a wide enough to grip all the runs or flights of the rope passing over the pulleys 7^a and 7^b. Thus, when the rope B' breaks or the power or pull end slips or is released, the runs b⁵ and b⁶ are clamped against the abutment 11^a and runs b⁷ and b⁸ clamped against the abutment 12^a. The crank 9^a of the dog E' is provided with a pull rope e so as to throw the dog E' to released or inoperative position, and the prop or member 13^a engages the teeth 17^a on the pulley 7^a to hold the dog E' released. The automatic setting of the dog E' takes place when the pull run b⁵ is slackened, just as in the case with the arrangement shown in Figs. 2 and 3.

From the foregoing description taken in connection with the accompanying drawing, the advantages of the construction and

method of operation will be readily understood by those skilled in the art to which the invention appertains, and while I have described the device which I now consider to be the best embodiment thereof, I desire to have it understood that the device shown is merely illustrative, and that such changes may be made when desired as are within the scope of the appended claims.

Having thus described my invention, I claim as new and desire to secure by Letters Patent:

1. A tackle block comprising a body, a pulley therein, a rope passing around the pulley, a clutch device having a plurality of gripping portions for automatically gripping the rope when the latter moves in one direction, manually-actuated means for throwing the device out of clutching relation to the rope, and a device for maintaining the clutching device in unclutching position.

2. A tackle block comprising a body, a pulley mounted therein, a rope passing around the pulley, a double end clutch dog arranged to grip the rope at a plurality of points when the rope moves in one direction, and a prop device disposed between the pulley and dog for holding the latter in inoperative position and adapted to be tripped by movement of the pulley in one direction.

3. A tackle block comprising a body, a pulley therein, a rope passing around the pulley, an abutment along which the rope travels, a dog for gripping the rope against the abutment, means connected with the dog for throwing the same to inoperative position, and a prop connected with and carried by the dog and arranged to engage the pulley to support the dog in inoperative position, and adapted to be automatically tripped as the pulley moves during the hoisting of a load.

4. A tackle block comprising a body, a pulley therein, a rope passing around the pulley, abutments along which the rope passes, a double-ended dog arranged to grip the rope against the abutments, a prop pivotally connected to the dog near one end to serve as a weight for causing the dog to automatically engage the rope, and manually actuated means connected with the dog for throwing the same to inoperative position and support the prop of the pulley, whereby the prop maintains the inoperative position of the dog.

5. A tackle block comprising a body, a pulley therein, a rope passing around the pulley, abutments along which the rope passes, a double-ended dog arranged to grip the rope against the abutments, a prop pivotally connected to the dog near one end to serve as a weight for causing the dog to automatically engage the rope, manually actuated means connected with the dog for

- throwing the same to inoperative position and support the prop of the pulley, whereby the prop maintains the inoperative position of the dog, and teeth on the pulley with which the prop engages for tripping the prop when the pulley moves in one direction.
6. A tackle block comprising a body, a pulley therein, a rope passing around the pulley, abutments along which the rope 10 passes, a double-ended dog arranged to grip the rope against the abutments, a prop pivotally connected to the dog near one end to serve as a weight for causing the dog to automatically engage the rope, manually actuated means connected with the dog for throwing the same to inoperative position and support the prop of the pulley, whereby the prop maintains the inoperative position of the dog, teeth on the pulley with which 15 the prop engages for tripping the prop when the pulley moves in one direction, a yielding cam on the prop, and a stop with which the cam engages for holding the prop in either of its extreme positions.
- 20 7. In a block, the combination of a U-shaped frame or yoke, said plates fitted to the yoke, a horizontally extending looped element passing through the yoke and having its ends arranged to form abutments, a pulley mounted between the plates, a rope passing around the pulley and crossing the said abutments, a dog mounted within the yoke and between the said abutments for gripping the rope against the latter, an axle 25
- for supporting the dog, a crank connected with the axle for throwing the dog to released position, and means for holding the dog in such released position.
8. A block including a frame, a plurality of pulleys, a rope having runs passing over the pulleys, abutments on the frame and along which the runs travel, and a single clutch element having its ends adapted to grip simultaneously a plurality of runs of the rope against the said abutments in case of breakage or slipping of the rope.
9. A tackle block comprising a body, a pulley therein, a rope passing around the pulley, a swinging clutch mounted in the body and arranged to grip the rope to prevent movement thereof in one direction and permit movement in the opposite direction, means for moving the clutch device to inoperative position out of engagement with the rope, and a prop having one end pivotally connected with the clutch device, and the other end free to ride on the pulley and assume a position for propping the clutch device in inoperative position after it has been manually removed from rope-engaging position.
10. In testimony whereof I have signed my name to this specification in the presence of two subscribing witnesses.
